UNITED STATES PATENT OFFICE.

LEOPOLD FUCHS, OF ROSLYN HEIGHTS, NEW YORK.

SUPPORT FOR LOOM HARNESS.

Application filed August 10, 1922. Serial No. 580,938.

To all whom it may concern:

Be it known that I, LEOPOLD FUCHS, a citizen of the United States, residing at Roslyn Heights, in the county of Nassau and State of New York, have invented certain new and useful Improvements in Supports for Loom Harness, of which the following is a specification.

The present invention has to do with improvements in loom apparatus, and in particular to novel supporting means for loom harness, as specially adapted for use in conjunction with fancy weaving or jacquard mechanisms in which the harness is connected to horizontally operating or reciprocating actuating devices, such as shown in my prior patent for improvements in jacquard mechanisms for looms, No. 1,214,449, dated January 30, 1917.

My invention has for its primary object the provision of means whereby the harness cords for weaving either wide or narrow ware may be so arranged as to maintain a spaced non-crossing or intersecting relationship, to thereby eliminate the wear incident to the chafing occurring in the usual arrangements, and the complicity of interlacing of the many cords which requires expert labor in the process of preparation for weaving operations. In other words, in the use or application of my invention, I am able to dispose the series of cords which are operated by any one of a horizontal row of griff bars in such relation to those of the next or adjacent row that they will lie in separate or spaced vertical planes, and to in this manner provide just as many of such vertical series as may be desired within the capacity of the harness actuating instrumentalities, without such cords crossing or interfering with one another.

A further object in view is to provide for the arrangement of the harness cords into distinct groups, as when weaving a plurality of fabrics, and the adjustment of any one group as a unit with relation to another group to best position the individual harness cords to accord with the width of the fabrics to be woven.

A still further object in view is to provide means for raising or lowering the harness cords, for varying the spacing between the cords with respect to their vertical series, and to adjust the vertical operating portions of the cords with relation to the batten of the loom.

My invention embodies further novel means cooperative with the harness cords whereby groups of the same may be shifted one with respect to the other, depending upon the width of the material which is to be woven, so as to best fix their position in relation to the prescribed spaces of the batten.

These and such other objects as may hereinafter appear are attained by the novel construction, combination and arrangement of parts to be hereinafter specifically described and claimed.

Reference will now be had to the accompanying drawings forming a part of this specification, wherein:

Figure 1 is a view in end elevation of my particular improvements applies to a Jacquard loom, such as when weaving a plurality of fabrics.

Figure 2 is a vertical sectional view showing one of the supporting frames for the harness cords in elevation, a portion of the spacing wires or members for the respective harness cords being omitted.

Figure 3 is a vertical sectional view through one of the supporting frames.

Figure 4 is a sectional view taken about on the plane indicated by the line 4-4 of Figure 3.

Figure 5 is a perspective view of a novel compass board used with my invention.

Figure 6 is a detail view of one of the removable spacing bars employed in the compass board.

Throughout the following detailed description, and on the several figures of the drawing, similar parts are referred to by like reference characters.

Referring to the drawings, A designates the loom frame which preferably includes transversely arranged bars or I-beams B, upon which the main feature of my apparatus is supported, as will be hereinafter described. Projecting laterally from the frame A of the loom are the supports C upon which the supporting frame D for the griff bars is mounted, such mechanism being clearly disclosed in my prior patent above mentioned. In the support D are positioned in horizontal rows a plurality of griff bars E, terminating in hooks with which the harness cords F are connected. These respective griff bars are actuated by means of horizontally reciprocating griff frames G, so as to give rising and falling movement to the

warp threads of a fabric. It is unnecessary to describe this type of jacquard mechanism, which is well known in the art, it being sufficient to indicate that the positioning of the harness actuating members horizontally necessitates provision being made to change the direction of motion of the harness cords from the horizontal planes to vertical planes, as is disclosed in my prior patent of which 5 the present mechanism is an improvement. Mounted upon the cross pieces B of the loom frame A are, in the adaptation illustrated, a series of supporting frames 1 over which the harness cords pass, so that these harness 10 cords will have vertically disposed portions lying over the warp threads. One of these frames only will be specifically described. The supporting means for the harness comprises a pair of clamping brackets 2 adjustably mounted upon the loom frame through 15 the instrumentality of the clamping screws 3. The supporting frame comprises the U-shaped holder 4 pivotally connected to the clamping brackets 2 by means of the pivot 20 bolts 5. The side members of the holder 4 are channel shaped so as to slidably receive the rectangular frame 6 carrying a plurality of spaced rods 7 of glass or the like, there being one of such rods for each horizontal row 25 of griff bars E of the jacquard mechanism. It will thus be seen that the harness cords of the lowermost row of griff bars, indicated by the reference character a, will pass over the lowermost rod 7, changing their direction 30 from the horizontal to the vertical, such vertical portion depending to a point adjacent the warp threads. Each of these harness cords of the row is connected to its proper coupling cord and mail through which the 35 warp thread passes. The next higher row of harness cords b of the horizontal row of griff bars pass over the second rod 7 of the frame and depend in close proximity to the harness cords a of the first row mentioned. 40 Without referring to the additional harness cords, the same arrangement applies to the various other series of harness cords c, d, etc. Within the frame 6 are mounted a series of vertical wires or spacing rods 8 held in their 45 spaced relation by means of the apertured reeds or holding bars 9, there preferably being employed one of such bars at the top, one at the bottom, and one centrally of the frame, and these bars hold the harness cords 50 of the respective rows separated or spaced properly apart.

Referring to the mounting of the frame 6, it will be observed particularly by reference to Figure 2 of the drawings that the said 55 sliding frame is held at adjusted position by means of the adjusting screws 10 carried by the bottom member of the holder 4, and by means of these screws the frame 6 may be raised or lowered in its holder for the purpose hereinafter specifically pointed out.

The harness supporting frame just described is normally positioned at an inclination and held in its inclined position by the clamping of the pivot member 5, but where more than one of such frames is employed 70 it is desirable to provide an auxiliary support such as disclosed in Figure 1 of the drawings, consisting of the side bars 11 which are connected to the jacquard support D by means of the fastening members 12. 75 Each bar is sustained by the necessary intermediate supporting standards 13 carried by the loom frame. Upon such side bars are mounted at each side of a frame 1 a pair of clamps 14, adapted to engage with the frame 80 and hold it in its fixed position.

It will be apparent from the foregoing that a wide range of adjustment of the harness is permitted by virtue of the arrangement hereinbefore described and now 85 to be further set forth. In the first place, the support D for the griff bars is shiftably mounted upon the support C and held in any desired position by means of the clamping screws 16, and a stop screw 17 is secured 90 to the loom frame at each side of the support D so as to hold this member at its fixed position. Obviously, movement of the support D toward the left will cause the harness cords to be raised and movement of this 95 support D in the opposite direction will effect lowering of the harness cords, speaking with reference to the vertical portions of the cords in each instance. Furthermore, 100 swinging of the frames 1 about their respective pivots 5 will likewise cause the harness cords to be raised or lowered, but more particularly this swinging adjustment of the frames is designed to control the position of the series of cords a with respect to the next 105 series b, and so forth, so that when it is desired to bring these series of cords into closer relation the frames 1 will be swung toward the jacquard, as when weaving narrow ware, while the swinging of the frame 1 in the opposite direction away from the jacquard will modify the position of the series of cords to increase the space between the same. The vertical adjustment or the 110 sliding of the frame section 6 upwardly or downwardly will obviously lift or lower the harness cords, and these various adjustments are provided in order that the disposition of the harness cords may be regulated both 115 with respect to each other and with respect to the spaces in the batten H through which the warp threads pass. All of the cords in the row a are held in their regular spaced order, separate and distinct from the cords making up the series b, and so forth, and the cords which depend from any one frame are capable of being adjusted as a unit by the movements or adjustment of that particular frame. All of the frames may be 120 simultaneously adjusted by the bars 11. 125 130

Hence it follows that any framed group of cords X may be adjusted with relation to another framed group of cords X as may be desired, to accord with the spaces in the 5 batten, or to accord with the width of the fabric which is woven. If the fabric is wide the frames 1 are adjusted closely together, whereas if a plurality of fabrics are being woven by the loom mechanism the frames 1 10 are separated into the position as shown in Figure 1. In order to maintain the harness cords in grouped relation with respect to the individual fabrics, I preferably employ, in conjunction with the supporting frames 1, 15 compass boards 18 constructed as shown in Figure 5 of the drawings. These frames are composed of the longitudinally arranged rods 19, 19', and transversely arranged rods 20, each of which is removably mounted in 20 its position to produce the proper index to accord with the weaving. The side member 21 of the compass board is formed with a flange 22 engaging about the I-beam J, while the opposite side member of the compass 25 board, indicated 23, is provided with a clamping or set screw 24 engageable with the contiguous I-beam J for securing the compass board in its proper position. By employing the compass boards in this manner 30 all the cords of a group X are maintained in close relation so as to fall directly vertically from this board to the warp threads, and said frames are individually adjustable as may be desired. The complicity of interlacing of harness cords is 35 greatly simplified by such an arrangement, so much so that unskilled labor may be employed for the purpose of preparing the looms for operation, and the removability 40 of the bars 19, 19', and 20 makes it possible to modify the index at will without disconnecting the harness cords from the jacks.

It will be observed in the drawings that 45 the vertical sections of the harness cords are attached to the horizontal sections at points adjacent to the frames 1, and in reference thereto I desire it to be understood that this arrangement may be modified as desired. 50 Other changes in the specific details of construction of the apparatus may be made without departing from the spirit of the invention and within the scope of the claims hereto attached.

Having thus described my invention, what 55 I claim as new and desire to secure by Letters Patent is:

1. In loom apparatus of the class described, the combination with jacquard 60 mechanism having horizontally movable harness actuating members and harness cords connected thereto, of pivoted adjustable supporting means on the loom over which the harness cords pass and are directed from a horizontal to a vertical plane,

and having means for sustaining the cords in separate non-intersecting planes.

2. In loom apparatus of the class described, the combination with jacquard mechanism having horizontally movable 70 harness actuating members and harness cords connected thereto, of supporting means pivotally mounted on the loom and adjustable about its pivot and also in a rectilinear plane to effect adjustment of the harness 75 cord with respect to the warp.

3. In loom apparatus of the class described, the combination with jacquard mechanism having horizontally movable 80 harness actuating members and harness cords connected thereto, of supporting means pivotally mounted upon the loom and having a member vertically adjustable to effect adjustment of the harness cord with respect to the warp. 85

4. In loom apparatus of the class described, the combination with jacquard mechanism and harness cords connected thereto, of supporting means over which the cords pass to dispose said cords in vertical 90 planes, said supporting means being slidably mounted for adjustment of the harness cords in a substantially horizontal plane with respect to the warp.

5. In loom apparatus of the class described, the combination with jacquard mechanism including horizontally movable 95 harness actuating members and harness cords connected thereto, of supporting means for said cords slidably mounted upon the loom 100 and having a member angularly adjustable relative thereto.

6. In loom apparatus of the class described, the combination with jacquard mechanism including horizontally movable 105 harness actuating members and harness cords connected thereto, of supporting means disposed at an inclination and over which the harness cords pass to hang in vertical 110 planes, said means having a section pivotally adjustable in the inclined plane of its disposition to raise or lower the harness cords with respect to the warp.

7. In loom apparatus of the class described, the combination with jacquard 115 mechanism including horizontally movable harness actuating members and harness cords connected thereto, of supporting means over which the harness cords pass to hang in vertical planes, said supporting means being shiftable bodily in a horizontal plane with respect to the jacquard to produce a raising or lowering of the harness cords with relation to the warp.

8. In loom apparatus of the class described, the combination with jacquard mechanism including horizontally movable 125 harness actuating members and harness cords connected thereto, of supporting means disposed at an inclination and pivotally 130

mounted to swing relative to the jacquard to thereby modify the relationship of the harness cords with respect to each other and means for adjusting said support in a plurality of different rectilinear planes.

9. In loom apparatus of the class described, the combination with jacquard mechanism including horizontally movable harness actuating members and harness cords connected thereto, of supporting means mounted adjacent to the jacquard and over which the harness cords pass to depend in separate vertical planes over the warp, said supporting means comprising a bracket and a frame swingingly mounted thereon, said frame being adjustable toward or from the jacquard to adjust the harness cord with respect to the warp and with respect to each other.
10. In loom apparatus of the class described, the combination with jacquard mechanism including horizontally movable harness actuating members and harness cords connected thereto, of supporting means mounted adjacent to the jacquard and over which the harness cords pass to depend in parallel vertical planes over the warp, means permitting adjustment of said supporting means transversely of the warp, and separate means for adjusting a part of the supporting means to effect raising or lowering of the harness cords with respect to the warp.

11. In loom apparatus of the class described, the combination of jacquard mechanism including a frame carrying harness actuating means and movably mounted at one side of the loom, adjustable harness cord supporting means connected to said frame, and means for shifting said frame to raise or lower the harness cord supports with respect to the warp.

12. In loom apparatus of the class described, the combination of jacquard mechanism including a frame carrying horizontally operated cord actuating means, harness cord supporting means connected to said frame over which the harness cord is passed to dispose the cord in a vertical plane, and means for shifting the frame of said harness cord actuating means as a unit to raise or lower the cord supporting means with respect to the warp.

13. In loom apparatus of the class described, the combination of jacquard mechanism including a frame carrying horizontally operated harness cord actuating means, an adjustable harness cord support connected to said frame and over which the harness cord is passed to dispose the same in a vertical plane, and means for shifting said harness cord actuating means as a unit to raise or lower the harness cord support with respect to the warp.

14. In loom apparatus of the class de-

scribed, the combination with jacquard mechanism including a frame carrying horizontally operated harness cord actuating means, a series of adjustable harness cord supporting frames over which the harness cords are hung in segregated groups, and means for adjusting said harness cord frames with respect to the warp connected for movement with the frame of said mechanism.

15. In loom apparatus of the class described, the combination of jacquard mechanism including horizontally operating harness cord actuating means, a series of harness supporting frames over which the harness cords are hung, and means for adjusting the supporting frames simultaneously to effect adjustment of the harness cords with respect to the warp.

16. In loom apparatus of the class described, the combination of jacquard mechanism including horizontally operated harness actuating means, a series of angularly arranged swinging harness cord supporting frames over which the harness cords pass to dispose said harness cords in vertical planes, and means for swinging said frames to thereby adjust the harness cords with respect to the loom batten.

17. In loom apparatus of the class described, the combination of jacquard mechanism including harness actuating means and harness cords connected thereto, a series of adjustable harness supporting frames over which said harness cords pass, and connecting means intermediate the same frames.

18. In loom apparatus of the class described, the combination of jacquard mechanism including harness actuating means and harness cords connected thereto, a series of adjustable harness supporting frames over which said harness cords pass, a connecting bar supported adjacent to the frames, and means on said bar cooperative with the respective frames to hold said frames in a predetermined position.

19. In loom apparatus of the class described, the combination with a jacquard arranged at one side of the loom, an adjustable harness cord frame mounted upon the loom adjacent to the jacquard for supporting the harness cords, a connecting member connecting the frame to the jacquard, and means for adjusting the jacquard to thereby adjust the frame and the harness cords supported thereon.

20. In loom apparatus of the class described, the combination of a jacquard arranged at one side of the loom, a series of harness cord supporting frames mounted upon the loom over the warp and adjustable relative to the jacquard and to each other, and a corresponding series of compass boards adjustably mounted beneath the frames and movable relative thereto.

21. In loom apparatus of the class described, the combination of a jacquard arranged at one side of the loom, a series of harness cord supporting frames mounted upon the loom over the warp and adjustable in a substantially horizontal plane, and a corresponding series of compass boards removably mounted beneath the frames and slidably adjustable in a plane substantially parallel to said frames to maintain the harness cords of their respective frames in proper relation to the batten spaces.
22. A harness support for loom apparatus comprising a bracket adapted to be attached to a loom, and means to secure said bracket in fixed position, a holder pivotally carried by said bracket, and a frame mounted in said holder and adjustable with respect thereto.
23. A harness support for loom apparatus of the class described, comprising a U-shaped channeled holder, a frame having side bars slidably mounted in said holder and a plurality of means for supporting the harness cords, fixed means for maintaining said cords in spaced relation, and means for sustaining the holder in position upon the loom.
24. A harness support for loom apparatus of the class described, comprising a holder, means for connecting said holder to the loom, a frame slidably mounted in said holder, a series of parallel supporting rods carried by said frame, and means for adjusting and holding said frame in said holder.

In testimony whereof I affix my signature.

LEOPOLD FUCHS.
